UNITED STATES PATENT OFFICE

2,499,715

WATER ACTUATED MOTOR

Noah W. Blevins, Roanoke, Va.

Application August 23, 1945, Serial No. 612,279

6 Claims. (Cl. 253—19)

1

This invention relates to pumps and has for its object to provide a force pump located slightly below a small stream of water by means of which it is actuated.

Another object of the invention is to provide in a pump a double lever operated by water for actuating the pump piston.

A further object of the invention is to provide in a water pumping system means for distributing a stream of water whereby a pump will be driven by the force of said water.

Other features and advantages will become more readily apparent from the following description and the accompanying illustrative drawings in which:

Figure 1 is a diagrammatic view illustrating my invention.

Figure 2 is an enlarged elevational sectional view of a pump housing and connection.

Figure 3 is an enlarged detail sectional view of a lever operating member.

Figure 4 is an enlarged top plan view of Figure 1.

Figure 5 is an enlarged sectional view taken on line 5—5 of Figure 1.

Figure 6 is a section on line 6—6 of Figure 5.

Figure 7 is a diagrammatic view of a slight modification.

By referring to the accompanying drawings it will be noted that my pumping apparatus 10, is located somewhat below a spring, or stream designated as A. The distance the apparatus is located below the water level a, is immaterial as long as all the operating elements of the device are below said line a, in order that the water will flow freely to said elements.

The pump housing 11 is substantially rectangular in shape and is formed to include the vertical walls 12, one of which supports a fulcrum 13 upon which the cylinder block 14 is pivotally mounted. An inlet end 15 for the cylindrical block 14 is provided and is connected to a flexible hose 16 which will be connected in any suitable manner with an elevated source of water supply A.

The inner ends 20 and 21 of the relatively long lever pipes 22 and 23 are secured to the block 14, while their outer ends 24 and 25 are secured to and support the tanks 26 and 27. Extending clean through the pipes 22 and 23 and the member 14, is a heavy wire rod 28, the ends 29 and 30 of which project into said tanks 26 and 27. Connected to the end 29 is a valve 31 adapted to open the port 32 into tank 26 when the member 22 is in raised position as indicated in Fig-

2

ure 1 of the drawings; and on the rod end 30 is mounted a valve 33 adapted to close port 34 of tank 27 when said tank is in its lowermost position as also indicated in Figure 1 of the drawings.

Pivotedly mounted as at 35 in the top wall 26 of tank 26 is a gravity actuated lever 36, on the outer end 37 of which is a weight 38. The lower and inner end 39 of the lever is pivoted at 40 to the inner end 29 of the rod 28. Fixed to the extreme end 28' of said rod is a downwardly projecting right angularly disposed elongated pin 41 which runs through and somewhat below a loop 42, the horizontal arm 43 of which has a right angular end 44, the terminal of which is fixed at 45 to a flap valve 46 adapted to close the outlet port 47 of the bottom wall of the tank 26. When element 22 is in raised position, the weight 38 will have thrown lever end 37 to the position shown in Figure 1 causing end 39 of said lever to draw rod 28 inwardly of the tank 26, and outwardly of the tank 27, this action causes arm 41 to push against end 42' of link 42 and the arm 44 to a position to close valve 46. In this position the valve 31 is open and valve 33 of tank 27 closed, causing water to flow into tank 26. This action reverses the action of like members in tank 27, pulling end 30 of rod 28 out drawing member 48 with it and causing link 49 to draw arm 50 to open the valve 51 to permit water to flow through port 52 from the tank 27. The action then again reverses and continues indefinitely. A support 53 for the rod end 30 is pivoted at 53' to the tank 27 and to said rod end 30.

Mounted on the lever arm 23 is a pump jack 55 pivotally connected to the outer end 56 of the piston rod 57 of piston 58 operating in pump cylinder 59. Between the spaced apart bottom walls 60 and 61 of housing 11 is formed a relatively small water receptacle 62 into which the lower end 63 of cylinder 59 opens. Also opening into the receptacle is a water inlet pipe 64 having a goose neck 65 from which the pipe extends to connect at 66 with inlet 19 of member 14. Located in section 67 of pipe 64 is a check valve 68. One end of the outlet pipe 69 connects at 70 with the receptacle 62 and connects at its other end at 71 with the storage tank 72. The flexible pipe 16 is connected at 73 to a supply pipe 74, the inlet end 75 of which opens into said water supply A.

Having now set forth and located the elements of my invention I will proceed to explain its operation. Water flows through the pipe 74 and through the flexible connection 16 to the distrib-

utting member 14, from whence it passes through the several ports thereof to pipe 64 filling receptacle 62 which is always full, then the water flows down through pipe 23 now stopped by valve 33, then the water flows up through pipe 22 through open port 32 and fills tank 26, the bottom valve 45 of which is closed. The weight of water in tank 26 causes it to drop to lowermost position throwing crank 38 to reverse position of rod 28, thereby opening port 34 allowing water to fill tank 27. With the same action the valve 45 is opened permitting water in tank 26 to escape, and as this tank thus becomes lighter, the heavier tank 27 goes down. This cycle continues indefinitely. As lever arm 23 goes up and down it operates the pump piston 58 drawing water into cylinder 59, and with it a fresh supply for receptacle 62 through pipe 64, which pipe is then checked by valve 58. The piston then goes down forcing its supply of water down into receptacle 62 which is already full, thus water therefrom is forced up into pipe 69 and on through the same and into tank 72. A check valve 76 in pipe 69 stops back flow of water from tank 72.

In Figure 7, I show a modification in which the inner end of rod 28 is supported in a bearing 77 through which said end is slidably supported. To the extreme end 78 of said rod end is fixed one end 79 of a lever 80, whose other end supports a thimble 81 rotatably mounted upon a pin 82. A hook 83 is fixed to the opposite and lower side of the thimble 81 and supports the end link of the chain 84. The other end of the chain is linked to the valve 85 eccentrically, whereby when the end 78 is forced inwardly, the lever 80 will rotate thimble 81 raising hook 82 and with it the chain 84 and valve 85. Reverse action on rod 28, of course, permits the valve to close by gravity.

It is to be noted that if desired the elements 65 and 67 may be disconnected and pipe 67 plugged and another pipe (not shown) connected to pipe 65, and run to a spring whereby the pump will be operated from the stream A, and water to tank 72 drawn from a spring or other source than said stream A.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

1. A device of the character described comprising a gravity motor including a support and a hollow cross head pivotally supported thereon for oscillatory movement, a water supply inlet conduit and a water discharge outlet conduit connected with the axial ends of said pivoted cross-head, laterally extending aligned pipes connected with said hollow cross-head at right angles to its pivotal axis for oscillatory movement therewith, tanks supported on the outer ends of said pipes, inter-connected inlet valves between the ends of said pipes and said tanks, dump valves in the bottoms of said tanks, and linkage between the

valves in each tank causing the inlet valve to close and the dump valve to open as the tank reaches its lowest position.

5 2. A device of the character described comprising a gravity motor including a support and a hollow cross-head pivotally supported thereon for oscillatory movement, a water supply inlet conduit and a water discharge outlet conduit connected with the axial ends of said pivoted cross-head, laterally extending aligned pipes connected with said hollow cross-head at right angles to its pivotal axis for oscillatory movement therewith, tanks supported on the outer ends of said pipes, inter-connected inlet valves between the ends of said pipes and said tanks, dump valves in the bottoms of said tanks, and linkage between the valves in each tank causing the inlet valve to open and the dump valve to close as each tank reaches its highest position.

10 20 3. A device of the character described comprising a gravity motor including a support and a hollow cross-head pivotally supported thereon for oscillatory movement, a water supply inlet conduit and a water discharge outlet conduit connected with the axial ends of said pivoted cross-head, laterally extending aligned pipes connected with said hollow cross-head at right angles to its pivotal axis for oscillatory movement therewith, tanks supported on the outer ends of said pipes, inter-connected inlet valves between the ends of said pipes and said tanks, dump valves in the bottoms of said tanks, and a pivoted counter-weight for mechanically actuating said valves as the tanks move upwardly and downwardly in their oscillatory movement.

15 25 30 35 4. A gravity motor including a support, a hollow cross-head including laterally extending hollow pipes pivotally supported thereon for oscillatory movement, tanks supported on the outer ends of said pipes, a wire rod extending through said pipes and into said tanks, first valves on said rod adjacent the said tanks, openings in said tanks, second valves seated in said openings and pivot means connecting said valves for alternate opening and closing of said first and second valves.

40 45 5. The combination of claim 4 wherein said pivot means includes a ring and pivot links terminating in said ring and secured to said valves.

50 6. The combination of claim 4 wherein a gravity lever is pivotally secured to said rods, and water inlet and water outlet conduits secured in said cross-head so that after water has filled one tank, the pipes oscillate to reverse position causing the gravity lever in said tank to pivot and open said first valve and close said second valve, the reverse action occurring in said other tank.
